UNITED STATES PATENT OFFICE

ARTHUR B. H. BAKER, OF PORTAGE LA PRAIRIE, MANITOBA, CANADA

GRAIN CAR DOOR

Application filed February 16, 1931, Serial No. 515,998, and in Canada May 5, 1930.

The invention relates to improvements in grain car doors and an object of the invention is to provide a grain car door which can be readily installed on the present grain cars and which can be easily and quickly opened by an attendant to free the grain to run from the car and which is constructed to effectively withstand the pressure of the grain when in use.

10 A further object is to construct a door embodying two similar right and left hand door sections normally spanning the doorway opening and locked together to withstand the pressure of the grain and adapted when unlocked to swing outwardly through the doorway opening under the pressure of the grain and thereby free the grain from the car, the outer ends of the sections at such times pivoting in respect to the door posts.

15 20 A further object of the invention is to provide a construction which permits the door sections to be readily moved to a stored position against the interior side wall of the car and which prohibits the removal at any time 25 of such door sections from the car.

A further object is to provide a grain tight door and in the furtherance of such object to provide means for drawing the outer ends of the door sections tightly against the inner faces of the posts as the said doors are being passed to their closed positions.

30 A still further object is to provide a simple, durable and effective means for reinforcing and releasably fastening the door sections together.

35 With the above more important and other minor objects in view which will become more apparent as the description proceeds, the invention consists essentially in the arrangement and construction of parts hereinafter more particularly described, reference being had to the accompanying drawings, in which:

40 45 Fig. 1 is an exterior view of a grain car provided with my door, the door being shown in closed position.

Fig. 2 is an interior view of the door and adjacent parts as they appear in Figure 1.

50 Fig. 3 is an enlarged detailed horizontal sectional view at 3—3 Figure 2.

Fig. 4 is an enlarged detailed horizontal sectional view at 4—4 Figure 1.

Fig. 5 is an enlarged detailed vertical sectional view at 5—5 Figure 2.

Fig. 6 is a perspective view of a portion of 55 one of the door posts showing a pair of guide tracks associated therewith.

Fig. 7 is a perspective view of one of the corners of one of the door sections.

Fig. 8 is an enlarged detailed horizontal 60 sectional view of one of the latches and associated parts as they appear in Figure 4.

In the drawings like characters of reference indicate corresponding parts in the several figures.

The doorway opening 1 is bounded by the customary door posts 2 and 3, lintel 4 and sill 5 and the doorway opening is spanned by my door, the details of which are hereinafter shortly described. The customary 70 outer closure door 6 is herein shown but such forms no part of the present invention as it is simply closed and sealed in the usual manner after the car has been loaded.

75 My door comprises two similar right and left hand door sections 7 and 8 of customary height and which are adapted to close the doorway opening, said sections at such time having their inner ends butted as shown and their outer ends extending to the inner 80 sides of the door posts. Both sections are of the same size and are identically constructed, each being provided at the exterior and at the upper and lower edges with reinforcing transversely extending metal bars 9 85 and 10 suitably bolted or riveted thereto. The outer ends of the bars are all provided on their outer faces with similar T-shaped heads 11 amply reinforced by webs 12 provided, the heads being inset somewhat from 90 the ends of the section in the manner best shown in Figure 7.

To the section 7 of the door, I secure permanently a vertically disposed metal plate 95 13 which in the closed position of the door sections laps the adjacent end of the door section 8 and prevents the escape of grain through the crack appearing between the ends of the closed door sections. It will be observed (see Figure 4) that when the sec- 100

tions are closed, the outer ends thereof lie to the inner sides of the post, that the inner ends thereof are butted and that the T-shaped heads 11 occupy at such time a position adjacent the inner corners of the posts.

Means are provided for releasably fastening the closed door sections together, such means also reinforcing the closed door sections. Said means embody upper and lower 10 hinges 14 and 15 each having one wing 16 permanently fastened to the outer face of the section 8 and another wing 17 extending in front of the section 7 and having the free end thereof provided with a horizontal slot 18, the slot receiving in each instance a locking latch 19 pivotally attached by a vertical pin 20 to a wing or plate 21 permanently fastened to the section 7. The latch in each 15 instance has the free end thereof horizontally slotted as indicated at 23 to receive the eye of an eye bolt 24 secured to the door section and a locking pin 25 is provided to pass through the eye in advance of the latch and lock the latch against swinging outwardly. 20 The locking pin is suitably attached to the door section by a chain or flexible line 26.

From the above, it will be obvious that one can easily and quickly lock the door sections together by passing the latches through the 30 slots 18, then swinging the latches to pass the eyes of the bolts through the slots 23 and finally passing the locking pins through the eyes in advance of the latches. The arrangement just described also reinforces the locked 35 doors against the outward bursting pressure of the grain within the car.

To the interior wall of the car at the sides of the posts, I locate similar upper and lower pairs of guiding tracks 27 and 28, the tracks 40 of each pair being arranged so that they provide a horizontally disposed bayonet slot 29 adapted to receive slidably the heads 11. In actual practice, the tracks are in the form of metal bars held in spaced relation from the 45 interior wall of the car by intervening wooden strips 30, the wooden strips being narrower than the metal bars and thereby providing the bayonet slots as best shown in Figure 5. The ends of the bars 27 and 28 adjacent the posts 50 are bent around the ends of the strips 30 in the manner best shown in Figure 6 to form pivot bearings 31 and they have their extremities permanently secured to the post by bolts 32.

55 According to this arrangement when the door sections are passed to closed positions, the T-shaped heads are received within the bearings 31 and the bearings and heads cooperate to form a pivot point around which 60 the door sections are compelled to rotate under the outward pressure of the grain upon the means locking the sections together being released.

When it is desired to store the sections, it is 65 simply a matter of shoving them endwise

into their stored position against the interior side wall of the car and at such time, the T-heads travel freely within the bayonet slots. Here I might mention that the outer ends of the pairs of bars 27 and 28 are turned inwardly so that the T-shaped heads are positively prevented from escaping from the bayonet slots in which they are received and accordingly neither door sections can be removed from the car in any position. In order to prevent grain accumulating on the lower bars 30, I have provided vertical holes 30' at intervals in said bars through which any lodged grain can escape.

The outer end of each door section is provided on its outer face with a vertically disposed filler strip 33 which prevents leakage of grain between said end of the section and the adjacent post when the section is in closed position. In order to insure of a grain tight joint being made between the outer end of the door section and the post in the closed position of the section, I have inclined the tracks as indicated at 27' and 28' (see Figure 6) slightly so that as the door sections are being passed to closed position, such inclined parts of the tracks will force the T-shaped heads towards the posts and in so doing jam the strips 33 tightly into contact with the posts. Guiding clips 34 are attached to the inner 95 wall of the car to guide the door sections as they are passed to stored position and to hold them positively against the interior side wall of the car when stored.

Assuming the door sections are in the closed position as best shown in Figure 4 and that it is desired to release the grain from the car, it is only necessary to release the locking pins and this allows the latches to swing outwardly and permit the wings 17 to escape therefrom at which time the door sections will simultaneously open under the pressure of the grain, such sections pivoting in the bearings 31. In their fully open positions, the said sections will be disposed at right angles to the car.

When it is desired to store the door sections, the wings 17 are folded back flat against the section 8 and the latches are folded back against the section 7. The door sections are then swung back to the position shown in Figure 4 and are then moved in a direction endwise of the car away from each other until they are wholly clear of the doorway opening in a position to the inner side of the side wall of the car and as they move into such stored position, the heads are travelling in the bayonet slots.

While I have entered into a detailed description of the various parts, it will be of course understood that they can be readily modified without departing from the spirit of the invention as set forth in the appended claims.

What I claim as my invention is:—

5 1. In a grain door for a grain car, pairs of guiding members secured to the interior wall of the car containing the doorway opening and forming upper and lower horizontally disposed key hole slots, a pair of similar door sections adapted to close the doorway opening with their inner ends butted and their outer ends to the inner sides of the posts,
10 heads permanently secured to the outer ends of the sections and slidably received within the key hole slots of the guiding members, said guiding members and heads being designed to permit of the out swinging of the
15 door sections under the pressure of the grain within the car and while retaining the door sections anchored to the car and means for releasably fastening the butted ends of the sections together to withstand the outward pressure of the grain within the car.

20 2. In a grain door for a grain car, pairs of horizontally disposed spaced tracks secured to the interior wall of the car containing the doorway opening, said tracks providing pivot bearings adjacent the posts, a pair of similar door sections spanning the doorway opening and having their inner ends butted and their outer ends located to the inner sides of the posts, heads secured to the
25 outer ends of the sections and slidably engaging the tracks, said heads and tracks co-acting to form pivots around which the door sections swing in opening outwardly and while retaining the sections anchored to the
30 car and means for releasably fastening the butted ends of the sections together.

35 Signed at Portage la Prairie this 26th day of February 1930.

ARTHUR B. H. BAKER.
